UNITED STATES PATENT OFFICE

GEORGE W. DOVER, OF PROVIDENCE, RHODE ISLAND, ASSIGNOR TO DOVERCRAFT COMPANY, INC., OF PROVIDENCE, RHODE ISLAND, A CORPORATION OF RHODE ISLAND

CURTAIN SUPPORTING MEANS FOR WINDOWS AND THE LIKE

Application filed January 13, 1931. Serial No. 508,413.

This invention relates to an improved curtain supporting means for windows and the like, and more particularly to a novel form of supporting means for use in conjunction with the usual curtain rod for supporting side draperies within and adjacent to the curtains in such position that the side draperies will overlie the outer side portions of the curtains as seen from the interior of the room, and will be supported in part by the curtain rod.

One object of the present invention is the provision of a novel combination of curtain rods and drapery supports which furnishes a simple and efficient means for supporting the window curtains and side draperies from common bracket members, and wherein the drapery supporting members are interconnected with the curtain rod in such a manner as to be held in part by the curtain rod and thus prevent the drapery supports from sagging under the weight of the draperies carried thereby.

Another object of the invention is the provision of a novel form of drapery support having a reinforced end portion and provided with a foldable attaching member for attachment to the curtain rod to assist in maintaining the drapery support in proper position relative to the curtain rod.

A further object of the invention is the provision of an extensible drapery support the length of which may be varied to adapt it to windows of different widths or to vary the effective width of the draperies relative to the curtains.

Other objects and advantages of the invention relate to various improved details of construction and novel arrangements of the parts as will be more fully set forth in the detailed description to follow.

Referring to the drawings:—

Fig. 1 is a front elevational view of the improved curtain supporting means as it appears when arranged in operative position upon a window frame with the curtains and draperies in position thereon.

Fig. 2 is a top plan view of the structure as shown in Fig. 1, and,

Fig. 3 is a rear perspective view of a por-

tion of one of the drapery supporting members illustrating the position of the parts and showing the foldable attaching arm in position either for attachment to the curtain rod or in its folded position for shipment.

In the embodiment of the invention illustrated herewith 1 designates a portion of the window or other frame to which the bases 2 of the brackets 3 are secured for supporting the curtain rod 4 and the drapery supporting members 5. The brackets 3 may each be provided with two or more outwardly positioned attaching arms 6 and 7 for receiving the looped end portions 8 and 9 of the curtain rod and drapery supporting members respectively.

The curtain rod 4 as shown is of oblong cross-section, although any other suitable or desired shape of rod may be employed, and is formed of telescoping channel shaped sections 10 and 11, one of which telescopes within the other to provide a structure which is adjustable in length to fit windows of varying widths. Each of said sections has a reinforcing member 12 inserted within one end thereof and provided with a looped end portion 8 for engagement with one of the bracket arms 6. The telescoping sections 10 and 11 are each provided with a bent portion 14 adjacent to one end thereof whereby the central portion of the curtain rod is located in spaced relation to the plane of the window frame when in operative position upon the frame.

Each of the drapery supporting members 5 is preferably formed from telescoping channel shaped sections 16 and 17, the end of one of said sections being adapted to telescope within the other to vary the effective length of the members 5 for use in connection with windows of varying widths or to increase or decrease the effective width of the draperies relative to the curtains. The channel shaped section 16 has a flat reinforcing member 18 secured in one end thereof, one end of the reinforcing member 18 being bent into substantially circular form, as at 19, to provide a pivot bearing for a hook member or arm 20 which is adapted to engage over the curtain rod 5 when the parts are in op-

of the drapery supporting member 5 from the curtain rod. An ornamental end plate 21 may be secured to the end of each section 16 in any suitable manner, and by a screw 5 or rivet 22 passed through the section 16, the reinforcing member 18 and the end plate 21, to secure the several parts firmly together. The channel shaped member 17 has a flat reinforcing member 23 fitted into one end thereof 10 and secured in place by having the adjacent portions of the channel shaped member bent closely therearound. The end of the reinforcing member 23 which projects from the channel shaped member is shaped into a 15 loop 9 for fitting over the bracket arm 7. The drapery supporting members 5 are each provided with a substantially right angle bend 24 so formed as to space the main portion of the drapery supporting member from the curtain rod 4 substantially uniformly 20 when the parts are in assembled position.

The hook member or arm 20 has a down-turned end portion 25 adapted to engage over the curtain rod to hold the drapery 25 supporting member 5 in spaced relation with the curtain rod, and the hook member or arm 20 is movable in the bearing 19 to be positioned at substantially right angles to the drapery supporting arm 5 or to lie there- 30 against as shown in full and dotted lines in Fig. 3.

What I claim is:—

1. In a curtain supporting means for windows, a curtain rod extending transversely 35 of the window, a drapery supporting member offset horizontally from a portion of said curtain rod, and pivoted means carried by said drapery supporting member and movable relative to said member into position to engage said curtain rod.
2. In a curtain supporting means, a curtain rod having the opposite ends thereof secured to a frame, a drapery supporting member having one end thereof secured to 45 the frame and provided adjacent to the opposite end with a pivotally mounted arm movable to engage a portion of said curtain rod or into proximity with a portion of said drapery supporting member.
3. In a curtain supporting means, a curtain rod having the opposite ends thereof secured to a frame, an extensible drapery supporting member comprising telescoping sections and having one end thereof secured 55 to the frame, an arm pivotally supported by said drapery supporting member adjacent to the end opposite to that which is secured to the frame, said arm being movable to engage said curtain rod or to lie in proximity with 60 said drapery supporting member.
4. In a device of the character described, a drapery supporting member provided with a portion located at one end thereof and adapted for detachable connection with a 65 bracket, a bearing carried by the opposite end

of said member, and an arm pivotally mounted in said bearing and capable of movement into a position at substantially right angles to said member.

5. In a device of the character described, 70 a drapery supporting member comprising telescoping sections, one of said sections being provided with means for attachment to a bracket, a bearing carried by the other of said sections adjacent to the free end thereof, and 75 an arm pivotally mounted in said bearing.

6. In a device of the character described, 80 a drapery supporting member comprising telescoping sections, one of said sections being provided with a reinforcing member having an end portion adapted for attachment to a bracket, the other of said telescoping sections being provided with a reinforcing member carried by the free end thereof, said last named reinforcing member having a bearing, 85 an arm pivotally mounted in said bearing and movable relative to said member into positions substantially parallel with said member or at approximately right angles thereto.

In testimony whereof I have affixed my 90 signature.

GEORGE W. DOVER.
